US0D1099279S

(12) **United States Design Patent** (10) **Patent No.:** **US D1,099,279 S**
(45) **Date of Patent:** **** Oct. 21, 2025**

(54) **FILTER ELEMENT**

(71) Applicant: **Wenzhou zhitai Techndogy co., Ltd**,
Wenzhou (CN)

(72) Inventor: **Xuefeng Chen**, Wenzhou (CN)

(73) Assignee: **Wenzhou zhitai Techndogy co., Ltd**,
Wenzhou (CN)

(**) Term: **15 Years**

(21) Appl. No.: **29/925,624**

(22) Filed: **Jan. 25, 2024**

(30) **Foreign Application Priority Data**

Jan. 22, 2024 (EM) 015048185-0001

(51) **LOC (15) Cl.** **23-01**

(52) **U.S. Cl.**

USPC **D23/209**; D30/132
